UNITED STATES PATENT OFFICE.

GEORGE L. TYLER, OF LYNN, MASSACHUSETTS.

LEATHER-SPLITTING MACHINE.

SPECIFICATION forming part of Letters Patent No. 253,449, dated February 7, 1882.

Application filed July 20, 1881. (No model.)

To all whom it may concern:

Be it known that I, GEORGE L. TYLER, of Lynn, in the county of Essex and State of Massachusetts, have invented a new and useful Improved Device for Adjusting the Feed-Rolls in a Machine for Splitting Leather, which device I will describe as follows, reference being made to the accompanying drawings, which form a part of this specification, like letters indicating like parts in the different figures thereof.

Figure 1 of the drawings shows my invention in perspective. Fig. 2 is a front elevation, Fig. 1, illustrating the back of the machine whereon my device is placed. Fig. 3 is a transverse vertical section cut through the two feed-rolls A, and represents the right-hand end of the machine when viewing Fig. 1. Fig. 2 is not of special importance for showing the invention itself, but is of use in that it makes a more complete illustration of the entire machine, so that the application of my invention to the machine may be more fully understood.

This invention is an improvement to be applied to the machine described and shown in Letters Patent granted to me dated May 24, 1881, numbered 242,079, and entitled "Machine for Splitting Leather."

This present invention consists in two adjusting arms, one of which is attached to each of the feed-rolls A by placing said arms upon journals at each end of each feed-roll. Each of said arms moves upon a pivot at each end thereof, so that the movement of the two ends 35 of the two arms at each end of the machine is similar to the operation of a pair of shears. The adjustment of the aforesaid arms is regulated by two equalizing-levers crossed at their centers and moving upon a pivot placed at the 40 point of crossing, said pivot forming a fulcrum. The tension of the feed-rolls is regulated by an adjustable elliptic spring attached to the upper and bearing upon the lower of the two adjustable arms B and B', said spring being placed 45 longitudinally of the feed-rolls, all of which will be hereinafter fully described. The most perfect adjustment of the feed-rolls possible is necessary, to the end that a piece of leather of any thickness shall be split exactly in the center thereof.

The springs described and shown in my patent above referred to, for the purpose of

adjusting the feed-rolls so that pieces of leather of varied thickness shall be split exactly in the center thereof, are omitted in this new device, 55 and the improvement used in place of said springs, which constitutes this invention, I will describe as follows:

The two adjusting-arms B and B' are placed over and upon the journals a of the upper and lower feed-rolls A, respectively. On one end of the machine the two adjusting-arms B and B' are placed over the two journals a in the ordinary manner; but in order to avoid making the adjusting-arms in two parts and bolting them together, which would of course weaken them, I think it better to attach said arms to said journals at one end of the machine in the manner shown at the two points x in Fig. 3—that is, by leaving the ends of the 65 adjusting-arms open, and merely slipping them over the journals a, as shown, for as said arms do not turn with said journals, and as they are held in place by the connecting-bars G and H, as will be hereinafter fully set forth, no more 70 secure fastening is necessary.

There is a connecting-bar, G, at each end of the machine, the one at the right-hand end being illustrated in Figs. 1 and 3. Said bars are pivoted to the adjusting-arms B and B' at 80 the points g and g', respectively. A bar, H, is placed at each end of the machine, and is bolted to the bar G and to the frame of the machine D at the points h and h', respectively. These two bars H hold the bars G and with them the 85 adjusting-arms B and B', thus preventing said adjusting-arms from moving up and down.

The two crossed equalizing-levers C are hung upon the pivot E, which pivot acts as the fulcrum for both levers. The four elongated slots 90 c are placed over the friction-bolts c', so that the spreading and contracting of the two equalizing-arms C are regulated and limited by the length of the elongated slots c.

J is an elliptic spring, each end of which 95 bears upon the adjusting-arm B', and the center of said spring bears against the under side of the arm B at the center of what may be called the "longitudinal" portion of said arm B—that is to say, the portion running longitudinally with the feed-rolls A. This elliptic spring J is for giving tension to the feed-rolls A, said tension being regulated by the adjusting-screw d.

The bolts *f* work sliding bearing-boxes within the frame at each end of the machine, and like bolts are placed on the under side of the machine for the purpose of preventing the feed-rolls *A* from coming together and striking the knife *L*.

The two feed-rolls *A*, the adjustable knife *L*, the guide *e*, and the gears and pulleys used for connecting and running said feed-rolls, all of which are seen in these drawings, are the same as those described and shown in my former patent, and operate in the same manner as therein described, so a description of them here is unnecessary. They are illustrated in these drawings merely that the application of my improvement to this machine before patented may be fully understood.

The operation of my invention is as follows: When a piece of leather is placed between the feed-rolls *A* at the front of the machine it is of course important that said piece of leather should be split in the center thereof, and it is to secure this end as perfectly as may be that my device is applied. When a piece of leather is placed between the feed-rolls said leather raises the upper feed-roll and lowers the lower one, and as the adjusting-arms *B* and *B'* are held firmly together by the two connecting-bars *G*, and as said adjusting-arms *B* and *B'* and bars *G* are held firmly from moving up or down by the two bars *H*, it is obvious that when a piece of leather is inserted between the two feed-rolls *A* the adjusting-arms *B* and *B'* will open at the ends thereof which are attached to the feed-rolls, and will open at both ends of the machine, and as said adjusting-arms are hung upon the pivots *g* and *g'* the adjusting-arms will open in a manner similar to the opening of a pair of shears.

The crossed equalizing-arms *C* insure the equal opening of both ends of the feed-rolls, and a piece of leather of a thickness proportionate to the length of the elongated slots *c* can be run between the feed-rolls *A*, such thickness being obviously the maximum, and of course any thinner piece than said maximum can be run through the machine, the elliptic tension-spring *J* being attached to and bearing against the adjusting-arm *B* and bearing upon the adjusting-arm *B'* in the manner shown and described, and said adjusting-arms being attached to the feed-rolls and being held to-

gether and in place by the bars *G* and *H*, respectively, it is evident that by turning the tension-screw *d*, and thus moving the tension-spring *J*, the tension of the feed-rolls *A* may be regulated. 55

What I claim as new, and desire to secure by Letters Patent, is—

1. In a leather-splitting machine, two adjusting-arms attached to the journals of two feed-rolls, said two adjusting-arms being held together by a connecting-bar at each end of the machine, and held firmly to the frame of the machine by a bar at each end of the machine, said adjusting-bars being adapted to spread and contract upon pivots, the whole constructed and arranged substantially as described, and for the purpose set forth. 60

2. In a leather-splitting machine, two equalizing-levers crossed at their centers, and held upon a pivot at said centers, said pivot forming a fulcrum for both levers, said levers being provided with an elongated slot at each end of each lever, each of said slots being 65 adapted to receive a friction-bolt, which friction-bolts are attached to the adjusting-arms *B* and *B'*, constructed and arranged substantially in the manner described and shown, and for the purpose specified. 75

3. In a leather-splitting machine, an elliptic tension-spring attached to and adapted to bear against the adjusting-arm *B* and to bear upon the adjusting-arm *B'*, said spring being provided with an adjusting-screw, *d*, constructed 80 and arranged substantially as described and shown, and for the purpose set forth. 85

4. In a leather-splitting machine, in combination with the two feed-rolls of a leather-splitting machine, the two adjusting-arms *B* and *B'*, the connecting-bars *G*, with pivots *g* and *g'*, the bars *H*, held by the bolts *h* and *h'*, the friction-bolts *c*, attached to said adjusting-arms *B* and *B'*, the two crossed equalizing-levers *C*, provided with the elongated slots *c* 90 and with the pivot *E*, and the elliptic spring *J*, with the adjusting-screw *d*, all constructed and arranged substantially as described and shown, and for the purpose set forth. 95
